UNITED STATES PATENT OFFICE.

ABRAM FREIMAN, OF NEWARK, NEW JERSEY.

DESIGN FOR A SAVINGS BANK.

Application filed December 1, 1927. Serial No. 24,356. Term of patent 3½ years.

To all whom it may concern:

Be it known that I, ABRAM FREIMAN, a citizen of the United States, residing in the city of Newark, county of Essex, and State of New Jersey, have invented a new, original, and ornamental Design for a Savings Bank, of which the following is a specification, reference being had to the accompanying drawing, forming a part thereof.

In the drawing,

Figures 2 and 3 are opposite side views respectively, of the bank showing my new design.

The lining in the drawing does not represent color.

I claim:

The ornamental design for a savings bank as shown and described.

ABRAM FREIMAN.
